UNITED STATES PATENT OFFICE.

RALPH GROSS, OF NEW YORK, N. Y.

SIGNALING APPARATUS.

Application filed February 12, 1927. Serial No. 167,800.

This invention relates to signaling apparatus and is an improvement over my U. S. Letters Patent No. 1,628,663, dated May 19th, 1927 and has for its primary object 5 the provision of an electrically controlled device actuated by means carried on the locomotive of a train for warning the engineer of the locomotive of any impending danger.

10 Another object is to provide colored signal lights within the cab of a locomotive, these lights being controlled by the same current and which indicate the entrance and exit of the train from the signal zone, these 15 signals being visible to an engineer irrespective of darkness.

Another object is to provide a mechanically operated register, also under the control of the same current, and having a recording 20 means actuated thereby.

Another object is to provide such apparatus in the form of a small compact attachment readily applied to a locomotive cab without any material change therein and 25 without interference with the usual paraphernalia contained therein.

Another object of the invention is to provide a generator on the locomotive from 30 which the signal apparatus may obtain its energy instead of taking it from the live wire or third rail usually disposed along the track.

A still further object resides in a signaling apparatus which includes a danger signal 35 with which a suitable means is employed for automatically applying the brakes of a train to bring the same to a complete stop.

With these and other objects in view, the invention resides in certain novel construction and combination and arrangement of parts, the essential features of which are hereinafter fully described, are particularly pointed out in the appended claim, and are illustrated in the accompanying drawing, in 45 which:—

Figure 1 is a side elevational view of a conventional locomotive operating on a track, and illustrating the application of the invention.

50 Figure 2 is an enlarged sectional view of the control box, mechanism therein and semaphore mast with arm, the section being taken on line 2—2 of Figure 3.

55 Figure 3 is a similar sectional view taken on a plane at right angles to Figure 2 on line 3—3 thereof.

Figure 4 is a diagrammatic view showing the signaling device as used in connection with a railroad switch.

Figure 5 is a diagrammatic view showing 60 the invention as used in connection with a railroad crossing signal.

In the drawing, the numeral 10 designates the road bed or trackway supplied with rails on which there is a locomotive 11, shown 65 as advancing towards a signal mast 12 having an arm 13 of the usual type pivoted near its top.

The arm 13 is movable by an arm 14, entering a switch box 15 secured to the mast, 70 and connected to a slotted lever 16 pivoted at 17, this pivot being the terminal for a conductor 18 leading to a conductor rod 18'.

The lever 16 may be actuated by any of the usual trackside signal control devices, 75 not shown, and is adapted to engage either of three contacts 19, 20 and 20^a within the box 15.

Alongside the trackway are masts 21 having downwardly bent spring loops 22 at 80 their upper ends, the downturned portion of these loops being uniformly directed towards the rails and provided with spaced insulators for carrying contact rods 23, 24, 24^a and conductor rod 18', the contact rods 23, 85 24 and 24^a being connected by conductors 25, 25^a and 26 with the contacts 19, 20 and 20^a respectively.

A hollow casing 27 having a transparent front 28 is secured in the cab of the locomotive closely adjacent its wall 11' and mounted on the outer side of the wall 11' are bowed spring contactors 29, 30, 30^a and 49 adapted to make wiping contact respectively 95 with the rods 23, 24, 24^a and 18'.

A small electro-motor 31 is mounted in the casing 27, the same being bolted to a transverse partition 32 in the lower part of the casing, this motor driving a reducing gear train 33, the last gear of which is fixed on 100 a spindle 34 mounted in the casing.

Fixed on the spindle is a drum 35 to wind a blank strip of paper 36 acting as a register, the blank being wound from another drum 37 mounted on a spindle near the top 105 of the casing.

Three styls 38, 39 and 39^a are pivoted on a rod 40, each being counterbalanced by a weight 41, and carried by the styls are armatures 42, 43 and 43^a, respectively operated 110 by electro-magnets 44, 45 and 45^a carried on the partition 32.

On top of the casing are light signals 46, 47 and 47^a, respectively red, green and yellow and these, together with the electro-magnets 44, 45 and 45^a and motor 31, are wired to receive current from the main conductor rod 18', as conveyed from the locomotive through spring contactor 49.

The wiring is so arranged that when the semaphore arm is in a lowered position current is conveyed from the conductor 18, lever 16, contact 19, conductor 25 and rod 23 to the contactor 29 and thence to the lamp 46, motor 31, electro-magnet 45 and dynamo 48 in parallel.

15 When the motor is energized, and the paper strip 36 is slowly actuated, the stylus 39 drawn into operative contact with it, recording a line equivalent to the duration of contact of the contactor 29 and rod 23.

20 When this contact becomes broken, the current is cut off and the motor ceases running; at the same time the red light 46 ceases to display a signal.

It will be appreciated that if the semaphore arm is moved into engagement with either of the contacts 20, 20^a, the circuits which they control will be closed when the contactors 30 and 30^a engage the respective rods 24 and 24^a to actuate the respective lights and other apparatus in these circuits.

Also employed in each of the parallel circuits of the lights, is an electric bell or audible alarm 50 which will sound when each respective circuit is closed to notify 35 the engineer of the exhibition of a signal, in the event that his attention is not attracted by the lights and the movement of strip 36.

To bring the train to an abrupt stop when the danger signal is operated and not 40 observed, I provide an electro-magnet 51 which is arranged in a circuit, is parallel with the red light 46 and which magnet when energized, attracts one end of a pivoted armature 52. The other end of the armature 45 is provided with a valve head 53 which normally seals the air brake line, 54, of the train. The valve is held in closed position by a spring 55, the tension of which is overcome by the energizing of the magnet 51. 50 When the magnet 51 is energized, the valve head 53 opens the air line, permitting the air to exhaust which automatically causes the brakes of the train to be applied. The valve is held opened by a latch member 56 which 55 automatically engages the armature 52 when actuated by the magnet, and in order to release the valve to permit it to return to a closed position, it is necessary for the engineer to manually disengage the same 60 from the armature 52.

A manually operable switch 57 is arranged

in the circuit with the magnet 51 so that the circuit may be deenergized when resetting the air valve 53.

In Figure 4 of the drawings, I have shown 65 the contactors 30 and 49 arranged in the circuit with the yellow light as shown in Figure 1 of the drawings and which serves as part of a circuit 58 which is controlled by a switch 59 operable by a rod 60 movable 70 with the rails of a railroad switch 61. The conductor rod 18' and the rod 24 are mounted along the track some distance in advance of the switch 61 so that if a rail road switch is open, the switch 59 is closed which in 75 turn closes the circuit 58 and forewarns the engineer by the lighting of the yellow light so that he may proceed with caution.

In Figures 1 and 5, I have shown an additional conductor 62 which is carried by 80 the locomotive and which is arranged in an electrical circuit 63 with the generator 48, conductor rod 18', contactor 49 and an added rod 64, which rod together with the rod 18' is adapted to be mounted about one-quarter 85 of a mile in advance of a railroad crossing. Also arranged in the circuit 64 is a signal 65 in the nature of a bell, and a visible signal 66 in the form of a light. The bell and light are disposed at the crossing to warn automobileists and persons that a train is approaching the crossing and beware of the same.

What is claimed as new is:—

In combination with a trackway having 95 roadside signals including a movable semaphore arm and a locomotive and the air brake line thereof, of masts arranged adjacent the roadside, spring arms on said masts, rods insulated from said spring arms and extending contiguous to the path of the 100 locomotive, contactors carried by said locomotive to engage with said rods respectively, a casing on the locomotive, lamps respectively red, yellow and green carried on said casing, an electric motor in said casing, a 105 drum driven by said motor, a rolled strip of material capable of receiving marks actuated by said drum, an electro-magnet arranged in circuit with each lamp, a stylus controlled by each magnet to mark selectively on said strip, means controlled by the position of said semaphore arm to energize said motor and selectively actuate the stylus, said means also causing selective illumination of said lamps, and means operable 110 by said semaphore arm when moved to one of its positions for exhausting the air from said air line.

In testimony whereof I have affixed my signature.

RALPH GROSS.
